UNITED STATES PATENT OFFICE

2,477,535

PIN RETAINER FOR DRAFT KEYS

Otto E. Wilson, Peru, Ind., and William H. Sale, Sanston, Va., assignors to T-Z Railway Equipment Co., Chicago, Ill., a corporation of Illinois

Application February 16, 1946, Serial No. 648,066

9 Claims. (Cl. 213—50.5)

1

The invention relates to draft gear for railway cars and more particularly to devices for preventing displacement from the draft key between the yoke and draw bar, of a retainer pin which holds the key in the draft sill of the car underframe.

One object of the invention is to provide simple and reliable means for preventing displacement of the retainer pin from the draft key.

Another object of the invention is to provide a simple device, including an angular slotted plate which is adapted to be permanently secured to the center or draft sill for preventing disconnection of the retainer pin from the key.

Another object of the invention is to provide a simple device for preventing displacement of the retainer pin from the draft key, which can be economically fabricated and is efficient in service.

Other objects of the invention will appear from the detailed description.

The invention consists in the several features hereinafter set forth and more particularly defined by claims at the conclusion hereof.

In the drawings:

Fig. 1 is a side elevation of a portion of a draft gear with the invention applied thereto.

Fig. 2 is a transverse section taken on line 2—2 of Fig. 1.

Fig. 3 is a section taken on line 3—3 of Fig. 2.

Fig. 4 is a perspective of the plate for preventing displacement of the retainer pin from the draft key.

Fig. 5 is a perspective of the retainer pin.

The invention is exemplified with draft rigging which comprises a channel shaped center or draft sill 10 which usually forms a part of the car underframe; a draw bar 12 and a yoke 16 which are disposed and suitably mounted in the sill 10 for cushioned movement, all of which may be of standard construction, as well understood in the art.

A draft key 18 which is usually flat in cross-section with rounded edges extends transversely through draw bar 12, yoke 16, elongated slots 20 in sill 10 for permitting movement of the draft gear in the sill for cushioned movement, as well understood in the art. The sides of the sill around slots 20 are re-inforced by plates 19 which are usually riveted to the inner faces of the sides of the sill. Key 18 is of sufficient length to project from the sides of the sill and is provided at one end with an integral head 21 and adjacent its other end with a cylindrical hole 22 for the reception of a retaining pin which includes

2

a cylindrical shank 24 and an elongated head 26 which is adapted to rest on the top face of the key by gravity for holding the shank 24 in the hole 22 of said key.

5 The invention comprises a plate, generally designated 27, and stamped from sheet metal, for preventing displacement of the retaining pin from the draft key while the draft gear is in service. Plate 27 includes an upstanding flange or member 28 which is suitably secured by rivets 29 or by welding to the outer side face of one side of draft sill 10 and an integral horizontally extending flange or member 30 which overlies the end portion of key 18 which projects from the sill and has a hole 22 formed therein. The horizontal flange 30 of plate 27 is provided with a longitudinally elongated slot 32 which conforms substantially to the contour of elongated head 26 of the retaining pin and through which said head is adapted to pass only when it is positioned longitudinally of the sill. A transversely extending slot 34 is cut through in flange 30 and communicates with slot 32 and its outer end is open to provide a side opening in plate 27 through which shank 24 of the retaining pin can be shifted laterally toward the sill, while head 26 rests or is positioned over the horizontal flange 30 of plate 27. When head 26 of the retaining pin is in vertical registry with the elongated slot 32 in member 30, head 26 will drop through slot 32 and onto the draft key 18 in which it will be held by gravity. The horizontal member 30 of the retaining plate 27 is disposed sufficiently close to draft key 18 so that shank 24 of the retaining pin will be retained in the draft key against upward displacement from said key, except when the head 26 of the retaining pin is in vertical registry with the elongated slot 32 in plate 27.

10 While the draft gear is in service, key 18 and the retaining pin are subjected to movement relatively to sill 10 and plate 27 and the retaining pin is free to rotate in the draft key, which eliminates the likelihood of all portions of head 26 of the retaining pin being vertically aligned with slot 32 in plate 27. For additionally insuring the displacement of the retaining pin from key 18, plate 27 is provided with an upstruck tongue 36 formed along the inner edge of slot 15 32 in member 30. Tongue 36 is joined at 31 to member 30 and its other end 38 is flexible. Tongue 36 is normally positioned to permit the head 26 of the retaining pin to pass through slot 32 in placing the pin in draft key 18. After the pin has been placed in the draft key, the

end 38 of tongue 36 is bent outwardly to form an abutment which will prevent the head 26 of the retaining pin from passing upwardly through slot 32. This effectively insures the retention of the retaining pin in draft key and prevents its displacement during service. Preferably, plate 21 around member 30 is formed with an integral depending re-inforcing flange 40 and is provided with indented angular ribs 41 in and between members 28 and 30 for providing upward flexing of the member 30 of plate 21.

The invention exemplifies a slotted plate which is adapted to be fixedly secured to one side of the draft sill for effectively preventing displacement of the retaining pin from the key. The plate is simple in construction and can be economically fabricated and installed on railway cars. In constructions heretofore used, it has been found that cotter pins when used to hold the retaining pin in the key are frequently sheared off and lost and therefore are not reliable in service.

The invention is not to be understood as limited to the details described, since these may be modified within the scope of the appended claims without departing from the spirit and scope of the invention.

Having thus described the invention, what we claim as new and desire to secure by Letters Patent is:

1. The combination with a draft sill having an elongated slot, a connecting key for a draw-bar and yoke, extending through the slot, and having one of its ends provided with a hole and projecting outwardly from the sill, and a retaining pin provided with a shank adapted to extend through the hole in the key, and a head for supporting the pin in the key, of a plate fixed at one side of the sill, overlying the portion of the key which carries the head of the pin, and provided with a slot through which the head is adapted to pass for insertion of the pin in the key, and with a side-slot through which the shank of the pin is adapted to pass, for positioning the head in registry with the slot for the head in the plate and means on the plate for obstructing the passage of the head through the slot after the pin has been inserted in the key.

2. The combination with a draft sill having an elongated slot, a connecting key for a draw-bar and yoke, extending through the slot, and having one of its ends provided with a hole and projecting outwardly from the sill, and a retaining pin provided with a shank adapted to extend through the hole in the key and a head for supporting the pin in the key, of a plate fixed at one side of the sill, overlying the portion of the key which carries the pin, and provided with a slot through which the head is adapted to pass for insertion of the pin in the key, and means on the plate for obstructing the upward passage of the head through the slot after the pin has been inserted in the key.

3. The combination with a draft sill having an elongated slot, a connecting key for a draw-bar and yoke, extending through the slot, and having one of its ends provided with a hole and projecting outwardly from the sill, and a retaining pin provided with a shank adapted to extend through the hole in the key and a head for supporting the pin in the key, of a plate fixed at one side of the sill, overlying the portion of the key which carries the pin, and provided with a slot through which the head is adapted to pass for insertion of the pin in the key, and integral means on the

plate, bendable to obstruct the upward passage of the head through the plate.

4. The combination with a draft sill having an elongated slot, a connecting key for a draw-bar and yoke extending through the slot, and having one of its ends provided with a hole and projecting outwardly from the sill, and a retaining pin provided with a shank adapted to extend through the hole in the key, and a head for supporting the pin in the key, of a plate fixed at one side of the sill, overlying the portion of the key which carries the head of the pin, and provided with a slot through which the head is adapted to pass for insertion of the pin in the key, and with a side-slot through which the shank of the pin is adapted to pass, for positioning the head in registry with the slot for the head in the plate, and means on the plate for obstructing the upward passage of the head through the plate after the pin has been inserted in the key.

5. The combination with a draft sill having an elongated slot, a connecting key for a draw-bar and yoke extending through the slot, and having one of its ends provided with a hole and projecting outwardly from the sill, and a retaining pin provided with a shank adapted to extend through the hole in the key and a head for supporting the pin in the key, of an angle plate integrally including a vertical member fixed to and projecting outwardly from one side of the sill and a laterally projecting member overlying the portion of the key which carries the pin and provided with a slot through which the head is adapted to pass for insertion of the pin in the key and with a side-slot through which the shank of the pin is adapted to pass into the slot for the head and means on the plate for obstructing the passage of the head through the slot after the pin has been inserted in the key.

6. The combination with a draft sill having an elongated slot, a connecting key for a draw-bar and yoke extending through the slot, and having one of its ends provided with a hole and projecting outwardly from the sill, and a retaining pin provided with a shank adapted to extend through the hole in the key and a head for supporting the pin in the key, of an angle plate integrally including a vertical member fixed to and projecting outwardly from one side of the sill, and a laterally projecting member overlying the portion of the key which carries the pin and provided with a slot through which the head is adapted to pass for insertion of the pin in the key, and with a side-slot through which the shank of the pin is adapted to pass into the slot for the head of the pin, and an integral tongue on the plate, bendable to obstruct the upward passage of the head through the plate.

7. The combination with a draft sill having an elongated slot, a connecting key for a draw-bar and yoke, extending through the slot, and having one of its ends provided with a hole outwardly of the sill, and a retaining pin provided with a shank adapted to pass through the hole in the key and an elongated head for supporting the pin in the key, of a plate fixed to the outside of one side of the sill and including a horizontally extending member overlying the portion of the key which carries the pin and provided with a longitudinally elongated slot through which the head is adapted to pass for insertion of the pin in the key, and means on the plate for obstructing the upward passage of the head through the plate after the pin has been inserted in the key.

8. The combination with a draft sill having an elongated slot, a connecting key for a draw-bar and yoke extending through the gear and through the slot and having one of its ends provided with a hole outwardly of the sill, and a retaining pin provided with a shank adapted to pass through the hole in the key and an elongated head for supporting the head in the key, of a plate fixed to the outside of one side of the sill and including a horizontally extending member overlying the portion of the key which carries the pin and provided with a longitudinally elongated slot through which the head is adapted to pass for insertion of the pin in the key and with a side opening through which the shank may be inserted in the slot and means on the plate for obstructing the passage of the head through the slot after the pin has been inserted in the key.

9. The combination with a draft sill having an elongated slot, a connecting key for a draw-bar and yoke extending through the slot and having one of its ends provided with a hole and projecting outwardly from the sill, and a retaining pin provided with a shank adapted to extend through the hole in the key and a head for supporting the pin in the key, of a plate integrally including a vertical member fixed to and pro-

jecting outwardly from one side of the sill, and an outwardly projecting member overlying the portion of the key which carries the pin and provided with an integral marginal flange, with a slot through which the head is adapted to pass for insertion of the pin in the key, and with a side-slot through which the shank of the pin is adapted to pass into the elongated slot for the head, and integral means on the plate, bendable to obstruct the upward passage of the head through the plate.
